SUPPORTING AND TURNING SLIP
FOR PIPESWilliam E. Barber, Houston, and George H.
Allen, La Porte, Tex.

Application April 30, 1949, Serial No. 90,578

1 Claim. (Cl. 24—263)

1

The invention relates to a combination supporting and turning set of slips for pipe in wells.

In the drilling of wells, particularly rotary method, various types of pipe, such as casing, drill pipe, and tubing, are lowered into and removed from the well bore during the drilling and producing operation. These pipes are connected end-to-end in being lowered into the well and disconnected section-from-section as they are removed from the well. During these operations the practice has grown up of supporting the pipe remaining in the well on a set of slips in a slip bowl which forms part of the well head.

The slip bowl may be in the casing or tubing head, in the blowout preventer or in the rotary table. It is usually in the form of a tapered bowl adapted to receive the tapered slips. Usually three or four jaws, or sections are employed as a set of slips so as to form a substantial circle around the pipe. The inside vertical faces of the slip jaws have teeth to bite into the pipe while the back tapered side rests against the slip bowl so that the wedging action of the tapered slip in and against the bowl serve to support the pipe.

In many instances it is desirable to rotate the pipe in performing a well operation and particularly in making up the threaded pipe joints the pipe in the well is usually held stationary while the section being added is rotated in order to be threaded to the pipe already in the well. In removing the pipe the threaded couples are unscrewed usually by holding the pipe in the well stationary and unscrewing the section or sections which are to be removed.

In some instances the slip bowl is rotated and the friction of the slips in the bowl turns the slip and the pipe.

In some instances of course the pipe rotates in the slip jaws and both sections of the pipe which are to be threaded or unthreaded must be gripped and oppositely turned or held.

The present invention contemplates a combination slip which may be manipulated not only to support the pipe but to also lock the pipe to the slip bowl so as to prevent relative rotation of the slip bowl and the pipe.

When the pipe is thus locked in the slip bowl if the slip bowl is held stationary the pipe is likewise locked in stationary position so that other sections of pipe may be threaded thereto or unthreaded therefrom. The string of pipe suspended in the slips is locked in position.

Another object of the invention is to provide a pair of locking and supporting slips so that the pipe is supported against downward vertical

movement and also supported against rotational movement.

Still another object of the invention is to provide a latching slip having an extensible portion therein which may be manipulated so as to project from the inside of the slip to engage the pipe being supported and to also project from the back onto the outside of the slip to engage the slip bowl to lock the pipe against rotation in either the slips or the bowl.

A still further object of the invention is to provide a slip jaw for supporting the pipe in wells wherein a latching bushing is carried for rotational movement in longitudinal position by the slip jaw so that the bushing which is eccentric may be turned to project on each the inside and the outside of the slip so as to latch against the pipe and the slip bowl.

Other and further objects of the invention will be readily apparent when the following description is considered in connection with the accompanying drawings wherein:

Fig. 1 is a sectional view of a typical form of slip bowl with the latching slip assembly shown in side elevation supporting a pipe in the slip bowl.

Fig. 2 is a section taken on the line 2—2 of Fig. 1 showing the slip and the latching mechanism in section.

Fig. 3 is a vertical section through the latching mechanism of the slip jaw and illustrating the pipe and the slip bowl.

Fig. 4 is a top plan view looking down on the slip bowl and the slips in pipe supporting position where the pivotal connection of the slip jaws and the handle of the latch have been illustrated.

Fig. 5 is a vertical sectional view through the slip bowl, slips, and pipe with a portion of the pipe broken away to illustrate the manner of engagement of the pipe by the latch bushing.

Fig. 6 is a transverse sectional view taken on the line 6—6 of Fig. 5 and illustrating the latching bushing as engaging the slip bowl and the pipe.

In Fig. 1 a slip bowl 2 is usually in the form of a spool having the lower flange 3 and upper flange 4 which are connected with the spool portion 5. The inside surface of this spool is tapered at 6 to provide a bowl for a set of slips 7. Such slips may be made of two, three, or more jaw sections. Three have been illustrated here. These jaw sections are seen in Fig. 2 at 8, 9, and 10. Each one constituting approximately one-third of an annulus. Each section has a smooth back, or outer surface 12, which is tapered to fit the taper

6 of the slip bowl. The respective jaws 8, 9, and 10 are shown as having been coupled together as in Fig. 4 by a handle 15 which has a bolt 16 which pivots the jaws 10 to the handle while the bolt 17 pivots the jaw 9 to the handle. Each jaw can turn with its respective bolt. An identical handle 15 is pivoted to the opposite side of the jaw 10 and to the jaw 8 as seen in Fig. 1.

As seen in Fig. 3 the inner surface of each of the jaw sections has horizontally extending teeth 20 which are arranged to engage the periphery 21 of the pipe 22. This pipe may be casing, drill pipe, or tubing, depending on the operation in the well.

It seems obvious that after the slips wedge into the bowl 6 that the teeth 20 grip into the periphery of the pipe and hold the pipe against further downward movement.

The particular contribution of the present invention is best seen in Figs. 1, 2, and 3 as having been incorporated in the slip where the jaw has been provided with a window 39 which is an opening extending entirely through the slip jaw. The jaw also has a vertical bore 31 which intersects the window 30 and is arranged to receive the latch rod 32 which extends above the upper end of the slip and is provided with a handle 33. The bore 31 extends below the window 30 and receives the lower end 34 of the rod 32 which acts as a bearing therefor.

The rod 32 is shown as having been reduced in size to provide a shoulder 36 which is arranged to abut a complementary shoulder 37 in the latching bushing 40 but may be merely eccentric. This bushing 40 is generally frusto conical or elliptical in shape with the larger end upward as seen in Fig. 1. The bushing is hollow to receive the rod 32 and is reduced in size at 39 to provide the shoulder 37. A cross pin 44 is shown as passing through the rod 32 and anchored in the bushing 40 so as to affix the bushing in non-rotatable position on the rod. The bushing may of course take various forms but as seen in Fig. 2 the bushing is more or less eccentric in shape having the vertical teeth 45 and 46 thereon which face in opposite directions on opposite sides of a diameter. The bushing may have the enlargements 47 and 48 on opposite sides so as to give a greater bearing surface diameter to the contact pipe and slip bowl. As seen in Fig. 2 the bushing is turned to unlatched position in that the two surfaces 47 and 48 of the bushing do not project radially inwardly nor outwardly beyond the peripheries of the jaw. The slips will merely act to support the pipe in the slip bowl without any rotational latch except the friction against the pipe and in the slip bowl.

In Fig. 6 it will be observed that upon turning of the handle 33 the bushing has been turned to such an extent that the periphery teeth thereof protrude beyond the inside and outside surfaces

of the jaw so that the slip bowl 6 is engaged on the outside and the periphery 21 of the pipe is engaged on the inside. This action of the eccentric bushing of course wedges the pipe against the other two slip jaws so as to increase the friction between the pipe and the jaws and also between the jaws and the slip bowl so that the pipe will be latched against rotation and in substance fixed in the slips and in the slip bowl.

10 The turning of the handle 33 releases the latch so that the pipe may turn and the slips readily picked up or pulled up when the pipe is removed.

The slant or taper of the rod 32 and handle 33 will cause the handle to swing outwardly and downwardly so as to keep the bushing in neutral. The slip is thus ready to be dropped into the slip bowl and will be in position to receive the pipe. A spring to urge the handle to such a neutral position may be provided. The handle may be readily turned to lock or latch the bushing, pipe, slip, and slip bowl.

15 Broadly, the invention contemplates a latching slip which may be used either to support a pipe in a well head or to serve a combination and dual function of both supporting the pipe and locking the pipe against rotation.

20 What is claimed is:

A combination make-up and back-up slip comprising a set of tapered jaws to support and grip the pipe in the well, latching means carried by one of said jaws to engage both the pipe and the slip bowl in which the slips are seated in supporting the pipe so as to lock the pipe to be rotated with or held stationary by the slip bowl, said means including a window in one of the slip jaws, a shaft turnable in said window and an eccentric latch bushing mounted on said shaft and having diametrically opposed enlarged portions thereon, said bushing being rotatable in said window to project one of said enlarged portions inwardly to engage the pipe and the other of said enlarged portions outwardly to engage the slip bowl, and a handle on said shaft to turn said bushing.
